[57] CLAIM

The ornamental design for a three-dimensional spiral kinetic sculpture, as shown and described.

DESCRIPTION

FIG. 1 is a perspective view of a three-dimensional spiral kinetic sculpture showing my new design in an expanded hanging condition;

FIG. 2 is a side elevational view thereof from a side opposite to that shown in FIG. 1;

FIG. 3 is a top plan view thereof;

FIG. 4 is a bottom plan view thereof; and,

FIG. 5 is a top plan view thereof in a collapsed non-hanging condition.
